Primary Examiner — Steven J Czyz(74) *Attorney, Agent, or Firm* — Wissing Miller LLP(57) **CLAIM**

The ornamental design for a trade show booth display, as shown and described.

DESCRIPTION

FIG. 1 is a front perspective view of a trade show booth display in accordance with the present design;

FIG. 2 is a side perspective view thereof;

FIG. 3 is a side view thereof;

FIG. 4 is a top perspective view thereof; and

FIG. 5 is a front perspective view thereof;

FIG. 6 is a left-side view thereof; and,

FIG. 7 is a top view thereof.

The broken lines depict portions of the article that form no part of the claimed design.
